ELECTRICAL PRECIPITATION APPARATUS

Harry J. White, Los Angeles, Calif., assignor to
Research Corporation, New York, N. Y., a corporation of New York

Application August 19, 1938, Serial No. 225,809

15 Claims. (Cl. 183—7)

The present invention relates generally to the art of electrically precipitating suspended particles from gases, and more especially to electrical precipitation apparatus of such nature as to collect the bulk of the particles in a space removed from the main gas stream passing through the precipitator.

Briefly, the operation of electrical precipitation consists in passing gases, containing suspended fine particles of either solid or liquid, through an electric field in which the particles become electrically charged by attachment of electrons or ions and are then attracted to an electrically charged member upon which the 10 charged particles are collected. It has been common practice to effect charging of the suspended particles by passing them between two opposed electrodes between which a high potential difference is maintained, one of the two electrodes 15 being a discharge electrode at which there is silent or corona electrical discharge that ionizes the gas and causes the suspended particles to become charged with the same electrical sign as the discharge electrode. This is termed charging action. The charged particles migrate, under the influence of the electric field between electrodes, toward the other electrode which is a non-discharging electrode of extended surface, and collect or become precipitated upon the 20 surface of the second electrode, which is consequently termed the collecting electrode.

In the following description and in the appended claims, the term "discharge electrode" will be understood to designate an electrode that facilitates corona discharge therefrom, because it has a configuration that establishes a sufficiently high potential gradient at or near its surface to create corona discharge before there is a disruptive discharge or spark-over. For this purpose the discharge electrode usually takes the form of a member of small surface area, such as a small diameter wire or a rod provided with sharp edges or points, whereby they may be created in the immediate vicinity thereof a sufficiently high electric field intensity to cause ionization and corona discharge. The term "non-discharging electrode" will be understood to designate an electrode that minimizes or prevents corona discharge therefrom because it has a configuration that establishes a sufficiently low field concentration at or near the surface to suppress corona discharge at elevated potentials lower than the voltage required for disruptive discharge or spark-over. For this purpose, a non-discharging electrode usually is one of extended surface area,

substantially free from sharp corners or other parts of sharp surface curvature at all portions which are located within the electric field, so as to substantially avoid ionization or corona discharge at that electrode.

Dust particles in the gas stream become electrically charged in the ionizing field and there migrate to the collecting electrode under the influence of the electrical forces exerted on them, and when the particles reach and are precipitated on the electrode the electric charges are neutralized or lost. The layer of dust particles on the electrode is exposed ordinarily to the gas stream which tends to blow off loose individual particles or agglomerations of particles, the erosion being a result of the gas velocity. The particles are held on the electrode more or less securely against erosion either by electrical forces or by the physical properties of the particles themselves. When the collecting electrode is within the range of the charging field, as in the single field type of precipitator, the field recharges and reprecipitates most of the particles that may be blown off the electrode, but even then some particles are blown along the electrode surface and off the outlet end of the electrode when the dust has such physical properties that the particles offer little resistance to gas erosion. There are some dusts that are particularly hard to collect for this reason, one typical example being "fly ash" which is composed of particles that have a generally spherical shape and have very little inherent tendency to adhere to the electrode or to each other. Characteristics such as these facilitate erosion of the precipitated dust layer by the gas stream, the particles that are picked up being carried away by the outgoing cleaned gases. Very little erosion takes place at low gas velocities and may be neglected, though the rate increases slowly with increasing velocity up to some velocity termed the "critical velocity" above which erosion loss increases rapidly with an increase in velocity and becomes quite appreciable. It is probably true of most dusts, if not all, that there is a critical velocity above which losses are appreciable. The present interest centers particularly around dusts for which the critical velocity is relatively low, since the amount of these dusts carried into the outgoing gas stream is considerable and makes it difficult to obtain high overall collection efficiencies at economic velocities. Obviously, the critical velocity for a given dust limits the capacity of a given treater if a minimum collection efficiency is to be obtained.

This collection difficulty is inherent in the dust being collected and has the effect of reducing the capacity of a unit of a given size operating at a given normal efficiency, because of the limitation 5 on dimensions required in order to keep the gas velocity below critical values. Expressed differently, the reduction in collection efficiency caused by erosion losses increases the size of the plant and equipment required to treat a given 10 volume of gas without falling below a minimum efficiency.

As might be expected, it has been frequently observed that the erosion losses are increased when the collecting electrode surfaces become 15 coated with deposited particles. Consequently, the percentage of loss is increased by relatively heavy dust loading of the gas stream and by the usual custom of shaking or rapping the collecting electrode at relatively long intervals, as these 20 circumstances keep down the total amount of time when the electrode is clean and therefore the erosion loss is the least. At present it is common practice to discontinue the flow through the precipitator section being cleaned for the 25 duration of the rapping period, to permit the deposit removed from the collecting electrode to settle down into the hopper in a quiet zone free of the gas stream. Obviously, rapping at short intervals with discontinuous flow is not resorted 30 to because it reduces the operation time of that section and, proportionately, the effective capacity of the treater.

It is thus a general object of my invention to provide an improved electrical precipitator in 35 which losses from erosion by the gas stream are minimized or eliminated and the collection efficiency is improved, particularly in the case of dusts having certain physical characteristics making collection difficult.

It is also an object of the invention to provide 40 an electrical precipitator adapted to continuous operation without need for discontinuing gas flow during the periods of cleaning, thus improving efficiency and capacity and eliminating the necessity of providing gas by-pass flues and dampers or an additional precipitator.

A further object is to increase the capacity of a precipitator of given size by decreasing erosion losses at any given gas velocity and so allowing, 50 higher gas velocities, especially in the case of dusts having low critical velocities in treaters of conventional types.

Another object is to provide an electrical precipitator that is adapted to handle a gas stream with a relatively high dust loading without loss 55 of collection efficiency from the accumulation of deposits on the collecting electrode.

These and other objects are attained in a precipitator constructed according to my invention 60 by providing in combination with a discharge electrode and a substantially non-discharging collecting electrode, a foraminous or pervious non-discharging electrode intermediate the discharge and collecting electrodes. The intermediate electrode forms a part of a system of collecting electrodes, as some dust particles collect 65 on it, though the bulk of the particles go through it and collect on the outer collecting electrode. The main gas stream passes parallel to the electrode 70 surfaces and is largely confined by the foraminous electrode and its mounting means to the space between the discharge and intermediate electrodes, in which space an ionizing field is maintained by suitable means. Another electrical field of a substantially non-discharging 75

character is preferably maintained between the intermediate and collecting electrodes to aid precipitation and to prevent redispersion of collected material into the gas stream, especially during rapping periods.

How the above objects and advantages of my invention, as well as others not specifically mentioned, are attained will be more evident from the following description and the annexed drawings, in which:

Fig. 1 is a vertical median section through an improved electrical precipitator constructed according to my invention;

Fig. 2 is a vertical median section taken at right angles to the plane of Fig. 1;

Fig. 3 is a horizontal section on line 3-3 of Fig. 1;

Fig. 4 is a horizontal section on line 4-4 of Fig. 1;

Fig. 5 is a vertical transverse section through a variational form of electrical precipitator constructed according to my invention, using plate type electrodes;

Fig. 6 is a vertical longitudinal section through the variational type of precipitator on line 6-6 of Fig. 5; and

Fig. 7 is a horizontal section on line 7-7 of Fig. 6.

Referring now particularly to Figs. 1 and 2, I shall first describe my invention as applied to a precipitator having four similar sets of electrodes which, with the exception of the discharge electrodes, are of the tubular type. The electrodes are enclosed within cylindrical housing 10 which, for convenience in manufacture and assembly, is 30 preferably made in three sections, the bottom, intermediate and top sections being indicated at 10a, 10b, and 10c respectively. Bottom section 10a contains mechanism for collecting and removing continuously the accumulated dust 35 taken from the gas stream, and this portion of the precipitator will be described in greater detail later. Inside this bottom section is an outer hopper formed by inclined plate members 11 and the housing side walls, the hopper being V-shaped in cross section, as shown in Fig. 2. Within and slightly above the outer hopper, is 40 an inner hopper 12 generally of diamond-shape cross-section as shown in Fig. 2. The bottom walls 14 of the inner hopper are parallel to and 45 vertically spaced above walls 11 of the outer hopper. Above each bottom wall 14 is a short length of vertical side wall 15; and a pair of sloping top walls 16 completely cover over the top 50 of the inner hopper. Walls 14, 15 and 16 extend horizontally until they intersect the vertical walls of housing section 10a, as shown in Fig. 1, so that the housing walls form the end members 55 of the hopper. As may be seen best from Fig. 1, gas inlet opening 17 in the housing wall opens 60 directly into the interior of hopper 12.

Within the upper portion of the housing is header plate 20 which may conveniently be held between the upper and intermediate sections 10b and 10c of the housing and which forms in the 65 upper section of the housing a gas chamber into which the gas from the electrodes is discharged before leaving the treater through gas outlet 21, which may be connected to any suitable gas conduit. Openings 22 in the side and top of the 70 housing are normally covered by plates and provide means for obtaining access to the treater interior for assembly and adjustment of parts.

Supported on header plate 20 and located centrally of housing 10, is vertically extending in- 75

sulator 24 which carries at its upper end four equally spaced, radially extending arms 25. A similar insulator arrangement is placed at the lower end of the housing and comprises insulator 27 which is supported centrally of the housing on bracket 27a attached to the inside faces of hopper walls 14. At the upper end of insulator 27, there are four radially extending arms 28 which are vertically aligned with arms 25. Between each pair of vertically spaced arms 25 and 28, there is stretched a wire 29 of relatively small diameter which forms a discharge electrode. As may be seen in Fig. 3, there are thus four such discharge electrodes spaced equally about the center of housing 10.

Surrounding each discharge electrode 29, is an intermediate electrode 30 in the shape of a cylinder or tube open at both ends. Intermediate electrodes 30 are made of screen, perforated metal, or other similar foraminous material that permits the passage of suspended particles from the gas stream through the electrodes to the collecting electrode, as will be more fully explained. Each electrode 30 fits snugly around an imperforate metal nipple 31 at the upper end of the electrode and against ring 32 on the nipple. Each nipple 31 is flanged at its upper end, the flange 31a resting upon the upper surface of header plate 20 while the nipple itself extends through a suitable opening in the header plate. Nipples 31 are preferably spot-welded to header plate 20 to hold them securely in place. The intermediate electrodes are held at their lower ends by similar construction, each tubular screen fitting snugly over an imperforate metal nipple 34 and resting upon a collar 35 attached to the nipple. Nipples 34 preferably have flanges at their lower ends by which they are welded or otherwise attached to top walls 16 of inner hopper 12, the nipples opening into the interior of the hopper.

The four collecting electrodes 38 are cylindrical members of sheet metal, of somewhat greater diameter than the intermediate electrodes 30, supported at their upper ends by horizontal plate 39 which is suspended by means of insulators 40 from header plate 20. Collecting electrodes 38 are conveniently supported from plate 39 by forming flanges 38a on the upper ends of the electrodes which are easily spot-welded to the plate. This holds the electrodes against undesired movement. Collecting electrodes 38 are held against lateral movement at their lower ends by transverse brace 42 which extends across the interior of the housing, and to which all the collecting electrodes are fastened as by welding. The upturned ends of brace 42 are provided with adjusting screw and clamping nut assemblies 43 which extend three horizontally elongated slots therein and bear against insulators 44 on the housing wall, thus electrically insulating the electrodes from the housing and at the same time permitting close lateral adjustment of the electrodes.

The electrodes thus far described are arranged in four independent groups operating in "parallel", each group comprising a tubular collecting electrode 38 and a tubular intermediate electrode 30 arranged concentrically of each other and coaxially of a discharge electrode 29. Four groups are placed in a single housing to obtain larger capacity than can be had with a single group which is the basis unit of the treater; and any number of electrode groups may be used according to the total gas capacity desired. As will

become apparent, each group of electrodes may be considered as comprising a discharge electrode and a collecting electrode system that includes the outer impervious tube upon which the bulk of the dust is collected and the inner porous tube upon which a portion of the dust is collected, but which is referred to as an intermediate electrode because of its position between the discharge electrode and the outer collecting electrode.

The rapping mechanism for cleaning the electrodes of accumulated deposits of precipitated particles includes two separate hammer systems that may be independently operated, there being one for the collecting electrodes and one for the intermediate electrodes. The first of these hammer systems adapted to rap the collecting electrodes consists of a transverse shaft 48 journaled at opposite ends in suitable bearings 50 mounted on the housing walls. At the mid-point of the shaft, is fastened hammer 51 which extends radially from the shaft a sufficient distance to strike against two anvils 52 which each consist of a short length of rod extending between two collars 53 rigidly fastened to one pair of collecting electrodes 38. In Fig. 2, the hammer 51 is shown in contact with an anvil 52, which is the position occupied by the parts just after a blow has been struck by the hammer to rap the right hand pair of collecting electrodes. Rotation of shaft 48 by means of handle 55 attached to one end of the shaft externally of housing 10 actuates the hammers; and by turning handle 55 in a direction to rotate shaft 48 counter-clockwise through a semi-circular arc, as viewed in Fig. 2, hammer 51 is brought into contact with the other anvil 52 and the second pair of electrodes may be rapped. In order to effectively insulate the collecting electrodes from the housing, shaft 48 is made of electrically non-conducting material such as wood that insulates metal hammer 51 from metal bearings 50 and housing 10, although it will be understood that it is not necessary that shaft 48 be one continuous insulating member, for it may also be a composite member having the necessary insulating sections. The same results may be secured by making the arms of hammer 51 of insulating material, or placing insulating sections elsewhere in the system.

A similar rapping mechanism is provided for jarring the intermediate electrodes to remove any accumulations on them. This second rapping mechanism comprises shaft 58 journaled in suitable bearings on the walls of housing section 10a and having a handle 59 on one end externally of the housing for oscillation of the shaft. Hammer 60 is fastened to the shaft midway of its length at the proper position to strike against the two U-shaped anvils 61 which are supported one from each top plate 16 of inner hopper 12 adjacent a pair of nipples 34. Oscillation of shaft 58 through a semi-circular arc by means of handle 55 causes hammer 60 to strike against anvils 61 alternately. The impact against an anvil vibrates the top wall 16 and nipples 34 and transmits the vibration to electrodes 38 from which accumulated dust is shaken by the jarring action. It will be understood that, although both rapping mechanisms are here shown as being manually operated for the sake of simplicity in the description and drawings, it is fully within the contemplation of the invention to mechanically operate both rapping mechanisms by any suitable type of mechanical drive. Particularly is this so, because mechanical operation of the

rapping mechanisms offers the advantage of automatic actuation of the hammers at short intervals, such as 30 or 60 seconds when the type of dust being precipitated out of the gas stream is such that better precipitation is obtained by cleaning the electrodes at frequent intervals. Obviously, the rapping mechanisms may be actuated at longer intervals when the character of the dust collected is such as to make this operation satisfactory, and in this case manual operation may be desired.

Dust shaken from the inside surfaces of electrodes 30 and falling down inside the electrodes, passes through nipples 34 into hopper 12 and collects in a narrow trough 64 at the bottom of the hopper. The dust from the inside surfaces of collecting electrodes 38 and that dust from electrodes 30 which falls on the outside of them, drops out of the electrodes on to the inclined hopper walls 16 and collects at the bottom of hopper 16 in a narrow trough 65. The dust in these two troughs is removed by a single continuous chain 68 which passes over idler sprocket 69 and driven sprocket 70, the latter being driven by motor 71 or 25 any other suitable source of power. As viewed in Fig. 1, the upper run of chain 68 moves towards the right and carries with it the accumulated dust in trough 64, the dust being carried into the housing around idler sprocket 69 until it builds up 30 sufficiently that it is carried out of the housing by the lower run of chain 68. This dust, together with the dust accumulated in trough 65 is then carried to the left, as viewed in Fig. 1, by the bottom run of chain 68 and discharged from the 35 precipitator housing through discharge opening 72, from which the dust falls into any suitable collecting means, such as a bin or other conveyor. There is preferably sufficient slack in chain 68 that it scrapes or drags along the bottom surface of both troughs 64 and 65, the troughs being but 40 little wider than the chain itself, so that the links of the chain keep the troughs scraped clean. The movement of chain 68 is preferably continuous, and its speed should be determined by the rate at which dust accumulates in hoppers 11 and 12.

45 The electrical conductor 75 connecting the discharge electrodes 29 to a source of high tension continuous or unidirectional current, indicated generally at A, is brought into the precipitator housing through insulator 76. A second conductor 77 is brought into the precipitator through insulator 78 and is used to connect the collecting electrodes 38 with a suitable source of high tension unidirectional or continuous current, indicated generally at B. The precise nature of the electrical means used to supply these high tension currents is not essential to the present invention, and it is not shown because such means are well known in the art and may take different forms depending upon various engineering considerations.

When the precipitator is in operation, the electrical apparatus maintains a high potential difference between discharge electrodes 29 and intermediate electrodes 30 which are electrically connected to housing 10 and therefore grounded, as it is customary practice to ground the housing, as indicated at 79, to prevent injuries to personnel and to stabilize the electrical conditions within the precipitator. This high potential difference 65 causes the formation of a corona or silent discharge at each of the electrodes 29, which are wires of sufficiently small diameter that their sharp surface curvature facilitates the formation of corona discharge before a disruptive or spark

discharge takes place between the electrodes 29 and 30. The charging or ionizing field maintained between electrodes 29 and 30 is of a character to charge electrically any particles carried through the field by the gas stream, the charge taken on by the particles being of the same sign or polarity as the discharge electrode.

The electrical apparatus also maintains an added non-discharging field between the intermediate and collecting electrodes, by maintaining a potential difference between electrodes 30 and 38. Since the intermediate electrodes are grounded, the collecting electrodes 38 are maintained at a polarity opposite to that of the discharge electrodes. Both the intermediate and 10 collecting electrodes have an extended surface free from sharp points or edges, or are otherwise constructed to suppress or minimize any tendency towards the production of a corona discharge from these electrodes. Consequently, the added 20 electric field maintained between the intermediate and collecting electrodes is a substantially non-discharging field which coincides in direction with the ionizing field and whose function is to precipitate the particles of suspended matter 25 previously charged in the ionizing field between the discharge and intermediate electrodes. As typical of voltages which may be applied to the electrodes, but without any limitation thereto, because the actual voltages used in any given 30 instance will be dictated by sound engineering design, it has been found in practice advantageous with a collecting electrode diameter of 8" and an intermediate electrode diameter of 6", to apply a potential of from 35,000 to 50,000 volts to 35 the discharge electrode and a potential of opposite polarity of from 12,000 to 18,000 volts to the collecting electrode. In accord with standard practice, it is preferred that the discharge electrode be negative and that the collecting electrode be positive. Thus, the conductor 75 is shown connected to the negative terminal of source A, and the conductor 77 connected to the positive terminal of source B, both of said sources having their other terminals grounded as indicated at 80.

40 During operation of the precipitator, a stream of gas carrying suspended particles to be separated or precipitated from the stream enters the treater through inlet 17 from a suitable gas conduit, not shown, which can be attached to the housing by means of the flange around the opening 17. Gas entering inlet 17 is introduced directly into inner hopper 12 which acts as an inlet header to distribute the gas to the four nipples 34 through which the gas flows into the ionizing fields. As the gas flows upwardly in a direction generally parallel to the electrode surfaces, the suspended particles are removed by the electrical precipitating action previously described, the clean gas then leaving the electrodes through nipples 31 and entering the space at the top of the treater. The clean gas then leaves the treater through outlet opening 21 and may be wasted to the atmosphere, or the gas may be conducted away for further use by means of a suitable gas conduit attached to the flange around opening 21.

60 It will be noticed that, as the gas leaves hopper 12, each nipple 34 directs an individual gas stream upwardly through one set of vertically extending electrodes, the stream being more or less confined throughout its entire vertical travel by the electrode 30. Because intermediate electrode 30 fits snugly around nipple 34 at the bottom end of the electrode, all of the gas is initially introduced into the ionizing field from

the nipple 34. Likewise, none of the gas can enter the top section and leave the treater except by first passing through a nipple 31 which withdraws gas only from the ionizing field. The 5 effect of the nipple 34 in directing the upward flow parallel to the electrode surfaces, together with the tendency on the part of the electrode 30 to confine the gas stream to the space inside the electrode, causes substantially all the gas 10 to flow in one main stream directly through the ionizing field, though a minor portion of it passes outwardly through the foraminous electrode 30 into the annular space between the intermediate and collecting electrodes, circulating in and out 15 through the intermediate electrode as a result of electric wind effects. This advantageous construction is permitted because the intermediate foraminous electrode is grounded. As pointed out above, the housing is grounded, and grounding the intermediate electrode eliminates the necessity of electrically insulating these two members. Consequently, it is possible to connect 20 some gas impervious directing member, such as hopper 12 and nipples 34, or header plate 20, to the housing walls, and at the same time have that member engage directly the intermediate electrodes at their ends where gas enters or leaves the ionizing field. The advantage is that all the incoming gas is introduced directly into 25 the ionizing fields, and none can first enter directly the space behind the tubular electrodes where the gas stream would not be exposed to the ionizing field.

Although the annular space between the intermediate and collecting electrodes is open at both the top and bottom of the collecting electrode 38, there is little or no tendency to create an eddy current of gas leaving the collecting electrodes and flowing into the housing. Consequently, the annular space surrounding each intermediate electrode constitutes a relatively quiet zone in which there is little or no gas movement.

The ionizing field radiating outwardly from a 45 discharge electrode terminates in part where it encounters the metal wires or portions of the opposed intermediate electrode 30; but where the ionizing field encounters an opening in the intermediate electrode, the field projects or continues 50 on through the opening and terminates on collecting electrode 38. The separate field independently maintained between the intermediate and collecting electrodes is effective in the annular space between these two electrodes, and is 55 superimposed on the parts of the ionizing field extending beyond the intermediate electrode. As a result of the fact that the total area of the openings in electrode 30 is normally considerably in excess of the area of the metal portions 60 of the electrode, and as a result of the field distribution mentioned, the bulk of the charged particles are carried on through the openings in the intermediate electrode under the action of the electric fields and are deposited upon the 65 inside surface of collecting electrode 38. A portion of the particles strike the intermediate electrode and become neutralized, thus becoming precipitated upon the intermediate electrode. A part of the particles so precipitated continue 70 to adhere to this electrode, while a part of them eventually are carried on through the openings in the electrode and are precipitated upon the collecting electrode. It is because of the fact that both the cylindrical electrodes oppose the 75 discharge electrode and have particles precipi-

tated upon their surfaces that the two of them may be considered as constituting a collecting electrode system which is made up of two separate electrodes that are electrically distinct and insulated from one another, but both of which operate to facilitate precipitation of the charged particles.

The two rapping mechanisms for cleaning the intermediate and collecting electrodes may be operated either mechanically or manually at such 10 intervals as may be necessary according to the rate of accumulation of dust deposits. It is a particular advantage of this form of treater that the rapping may be carried out at very short intervals, of the order of 30 to 60 seconds if 15 desired, to give the effect of a continuous shaking or cleaning action on the electrodes, because the gas flow through any one of the electrodes need not be discontinued during the cleaning operation. As mentioned, above, the largest part 20 of the precipitated particles collect eventually upon the inside surface of a collecting electrode 38, and when they are jarred off the surface they fall downwardly within the annular space between the collecting and intermediate electrodes 25 which is a quiet zone relatively free from gas flow. Consequently, the dust deposits from the collecting electrodes 38 and from the outer surfaces of the intermediate electrodes 30 fall downwardly out of the electrode system without being 30 picked up by the upwardly moving gas stream, and are collected in the outer hopper 11 which is entirely separated from the incoming gas. The dust deposits shaken loose from the inner surfaces of the intermediate electrodes tend to fall 35 downwardly through nipples 34. However, this dust is brought into contact with the upwardly rising gas stream. The larger agglomerates of precipitated particles settle down within hopper 12, but a few of the smaller agglomerates or individual particles are again picked up and carried suspended in the gas stream. These re-suspended particles are again subjected to the 40 charging and precipitating action of the electric fields within the electrodes and will eventually 45 either be precipitated on the collecting electrode surfaces or will accumulate in large agglomerates which will fall down in hopper 12 to the trough 64 at the bottom of the hopper. Because of this 50 improved operation of the precipitator constructed as described, the electrodes may be rapped at such frequent intervals as to be kept in a substantially clean condition at all times and thus operate at highest precipitation efficiency without in any way decreasing the 55 capacity of the treater as a whole by discontinuing gas flow through any portion of it during the cleaning period.

As an example of the advantages derived from my improved type of precipitator, the following 60 typical laboratory tests may be cited. In one such trial run made to determine the collection efficiency of the precipitator with respect to "fly ash", which is a dust that is extremely difficult to collect because of the spherical shape and 65 non-adherent character of its particles, it was found that the loss of dust from the outlet end of a single tubular collecting electrode without any intermediate electrode 30, amounted to 10% of the dust introduced at the inlet end of the 70 electrode at a volume of 80 cubic feet per minute of gas. Insertion of a foraminous intermediate electrode between the collecting and discharge electrodes decreased the dust loss from the precipitator to 1% at the same gas volume. That is, 75

at the same capacity the quantity of dust carried in the outlet gas stream was reduced to one-tenth its former value. It was also found that the capacity of the same precipitating unit could be increased to 190 cubic feet per minute without exceeding the former loss of 10%, that is, with a collection efficiency of 90%. This last experiment was carried out with both the collecting and intermediate electrodes grounded so that no precipitating field was maintained independently between them.

The effectiveness of the non-discharging field is emphatically demonstrated by a later set of tests using a slightly higher potential at the discharge electrode, in which the capacity at 90% efficiency was determined to be 215 cubic feet per minute with both the intermediate and collecting electrodes grounded. When a high potential was applied to the collecting electrode, it was found that the capacity of the treater could be increased to 465 cubic feet per minute without dropping the collection efficiency below 90%, and that the efficiency was increased to 98% at the initial flow of 215 cubic feet per minute. All these tests were run on "fly ash" because that material is hard to collect. Other tests show that the increase in capacity or efficiency depends on the kind of dust treated, being greatest for those materials that are hard to collect in a conventional precipitator of the single field type.

Experiments on various other types of dust uniformly show a marked increase in capacity or improved collection efficiency or both as a result of having a foraminous intermediate electrode between the discharge and collecting electrodes to form adjacent the collecting electrode a quiescent zone in which the dust is collected or precipitated on the collecting electrode and which is sufficiently free from disturbance by the gas stream that there is little or no tendency for the dust to be redistributed into the gas stream even when the electrodes are being shaken for cleaning. The tests also show uniformly a still greater increase in capacity at the same collecting efficiency, or a greater increase in efficiency at the same capacity, as a result of maintaining an independent substantially non-discharging field between the intermediate and collecting electrodes which facilitates precipitation of the particles on the collecting electrodes and amplifies the effectiveness of the collecting electrode system comprising two separate electrodes.

Figs. 5, 6 and 7 illustrate a variational form of precipitator which is fundamentally the same as the precipitator already described, except that the intermediate and collecting electrodes instead of being tubular in shape are now plate-like in shape and other minor changes in the shape and arrangement of parts have been made. As shown in these figures, the precipitator is enclosed within housing 85 of rectangular cross-section through which the gas stream flows in a generally horizontal direction from inlet 86 to outlet 87, the bottom of the housing being provided with inclined walls to form one or more hoppers in which the dust falls after being shaken from the electrodes. The dust may be removed from hopper bottom of housing 85 by any suitable type of conveyor or valve mechanism, which is not shown in the drawings as these devices are well known in the art.

The typical precipitator illustrated in the drawings is composed of two groups of electrodes,

each group comprising discharge, intermediate, and collecting electrodes and each group being a substantial duplicate of the other group. The discharge electrodes 88 are a series of wires of relatively small diameter arranged in a vertical plane and suspended between horizontal members 89 which form the upper and lower members of a generally rectangular frame. The supporting framework for the discharge electrodes also includes cross members 90 and vertical posts 91 designed to hold longitudinal members 89 vertically spaced at the proper interval and to maintain the discharge electrodes of the two groups in parallel spaced vertical planes. This supporting framework is mounted upon insulators 93 carried on brackets attached to the walls of housing 85 in order to electrically insulate the discharge electrodes and their supporting structure from the housing walls, which are grounded in accordance with common practice. The discharge electrodes may, of course, be held in place by any other suitable structure electrically insulated from the housing and the other electrodes.

On each side of a series of discharge electrodes and parallel to the plane thereof, is a foraminous intermediate electrode 94 which is in the form of a sheet or plate. Intermediate electrodes 94 may conveniently be suspended from the top wall of housing 85 and are connected directly thereto since it is preferred that these electrodes be grounded through their electrical connection to the housing. The intermediate electrodes may be of any foraminous construction, such as is afforded by the use of wire screen or perforated metal sheets; and are preferably bounded on their vertical and bottom sides by an imperforate border 95 which strengthens the electrodes against flexing and helps direct and confine the entering gas stream to the space between the discharge and intermediate electrodes. For the latter reason, borders 95 are gas impervious and at the vertical edges of the intermediate electrodes 94 are shaped to prevent any direct flow of the incoming gas stream into the space behind the electrodes, thus the only gas behind the electrodes is that which passes through the perforate portions of electrodes 94 after having once entered the ionized field. The vertical portions of margins 95 of electrodes 94 adjacent the side walls of the housing are bent through an angle of 90° and joined to the vertical side walls in a suitable gas tight manner. In the central portion of the precipitator, the vertical portions of margins 95 of two electrodes 94 are formed in a U-shape, thus connecting together two intermediate electrodes into the form of a hollow envelope. This construction is shown best in Fig. 7. Borders 95 extend upwardly and are connected to the roof of the housing in order to prevent gas from leaking around the edge of the electrode, but may be left open at the bottom in order to facilitate removal of dust from the electrodes, since gas entry at this point is negligible in any event. As a consequence of this construction, the main stream of gas flows parallel to the electrode surfaces and through the space between the discharge and intermediate electrodes where the ionizing field is maintained.

Although the velocity of flow is usually sufficient to carry the main stream of gas through the precipitator without creating any material disturbance in the lower hopper portion of the housing, it may be found desirable to provide baffle means for further confining the gas flow to 75

the horizontal passages between electrodes 94. A suitable arrangement of baffles includes a main baffle member 97 at each end of the electrodes. Each baffle 97 extends horizontally the entire 5 distance between the side walls of housing 85 and extends downwardly from a point below the discharge electrode frame, determined by electrical considerations, to a point well within the hopper bottom of the housing but preferably not 10 entirely to the bottom wall of the housing. Baffles 97 are preferably secured in place as by welding and may be used as supports or braces, as will be described. A number of small subsidiary baffles 98 of limited vertical extent may 15 be placed advantageously between the two intermediate electrodes on opposite sides of a series of discharge electrodes, as shown in Fig. 5. The top edges of these subsidiary baffles 98 are placed at the same level as the top edges of baffles 97, 20 that is, not within arcing distance of electrode frame members 89, but the subsidiary baffles extend downwardly only to the bottom of marginal portions 95 of the intermediate electrodes. Main baffles 97 greatly impede any gas flow directly into the lower portion of the housing from the regions at the ends of the electrodes, especially from inlet 86, while the subsidiary baffles act as deflectors that substantially eliminate any 25 tendency for the gas to flow downwardly into the hopper bottom of the housing from the spaces between the electrodes. In this manner a quiescent zone is assured not only at the sides of the intermediate electrodes removed from the discharge electrodes, but also in the lower portion 30 of the housing into which the dust falls when it is jarred from the electrodes.

The collecting electrodes 100 are suspended from the top wall of housing 85 by insulators 101 and are held against lateral movement at their 40 lower ends by insulators 102 which are attached to baffles 97. In this way these electrodes 100 are electrically insulated from the frame and from the discharge electrodes in order that a separate potential may be applied to the collecting 45 electrodes. The collecting electrodes are in the form of imperforate plates extending parallel to the intermediate electrodes and the planes of the discharge electrodes, there being a collecting electrode at each side of the precipitator 50 between intermediate electrode 94 and the side wall of the housing, while at the center a single collecting electrode 100 may be used for both intermediate electrodes, since both faces of the collecting electrode are available for collecting 55 surfaces.

Thus, as in the form of the invention previously described, a foraminous non-discharging electrode is provided intermediate each discharge electrode and an opposing collection electrode, 60 and the intermediate electrode and collecting electrode constitute together a collecting electrode system.

Just as in the form previously described, there are provided separate rapping mechanism for the 65 collecting and intermediate electrodes. A rapping mechanism is provided for each pair of intermediate electrodes, and comprises shaft 105 journaled in bearings 106 supported in the end walls of housing 85 and baffles 97. A suitable 70 number of hammers 107 are attached to shaft 105 to deliver the desired blows. Shaft 105 is located midway between the pair of intermediate electrodes which it raps, and the hammers are of sufficient length that oscillation of shaft 105 through 75 a semi-circular arc causes the hammers to strike

alternately against the lower edges of the two intermediate electrodes, as shown in Fig. 5. Dust jarred loose from these electrodes falls down into the hopper bottom of housing 85.

Similar rapping mechanism is provided for the 5 collecting electrodes and comprises a shaft 110 located midway between each pair of collecting electrodes 100 and journaled in bearings 111 mounted on the housing walls and baffles 97. A suitable number of hammers 112 are secured to 10 shaft 110 and the hammers upon oscillation of shaft 110 through a semi-circular arc, strike against the lower edges of the collecting electrodes. One shaft 110 and its attached hammers, is used to clean two collecting electrodes, as the 15 hammers strike alternately against the electrodes; and where an odd number of collecting electrodes is used as shown in Fig. 5, the hammers are staggered along the length of the two shafts 110 in order that the hammers will not 20 interfere with each other if they swing simultaneously towards the same electrode. Shaft 110 is either made of non-conducting material, or else has insulating sections arranged along its length, in order that the collecting electrodes will 25 not be grounded or short-circuited through the rapping mechanism during the cleaning operation. Although no operating mechanism is shown, it will be understood that the several rapping mechanisms may be actuated by either me- 30 chanical or manual means attached to shafts 105 and 110 and adapted to oscillate these shafts at suitable intervals of time.

Suitable electrical apparatus and connections, 35 not shown, are employed to apply a high potential current to the electrodes and maintain between the discharge and intermediate electrodes an ionizing field as a result of the corona discharge around electrodes 88. A separate and independent electric field is preferably maintained 40 between the intermediate and collecting electrodes, but this field is of a substantially non-discharging character. It is preferred that the intermediate electrode be grounded and that the discharge and collecting electrodes be maintained 45 at opposite potentials or polarities in order to maintain both the fields in the direction that forces charged particles toward the intermediate and collecting electrodes.

In general, the operation of the last described 50 form of my invention is the same as described in connection with Figs. 1 to 4; and the collecting electrode systems comprising a foraminous intermediate electrode and a plate collecting electrode offer the same advantages of increased 55 capacity and collecting efficiency as compared with a single plate collecting electrode, that are found in the use of electrodes of tubular shape. Since in this form of precipitator the gas stream is directed horizontally through the treater, the lower 60 portion of the housing is free from disturbance caused by the incoming gas stream flowing through it as through hopper 12, and the collection of dust falling off the electrodes is somewhat simplified, only a single hopper being necessary in this case.

In the first form of the invention described above utilizing tubular electrodes, it is preferred 65 that the collecting electrodes be imperforate; but in the second form described, it may be desired under some circumstances to replace the plate type collecting electrodes with perforate or gas pervious electrodes, as for example, with the "rod curtain" type of collecting electrode which is 70 75

more easily cleaned by rapping than is the plate type.

Having described typical embodiments of my invention, it will be apparent that various changes in the shape, construction, and arrangement of parts may be made without departing from the spirit and scope of my invention; and therefore it is to be understood that the foregoing description is illustrative of, rather than limitative upon the invention set out in the appended claims.

I claim:

1. In an electrical precipitator through which flows a stream of gas carrying suspended particles to be removed, the combination of a discharge electrode; a substantially non-discharging collecting electrode; a foraminous substantially non-discharging electrode intermediate the discharge and collecting electrodes; means for maintaining a high potential ionizing field between the discharge and intermediate electrodes; means for independently maintaining a non-discharging precipitating field between the intermediate and collecting electrodes; and means for directing the main stream of gas into, through, and out of the space between the discharge and intermediate electrodes in a direction substantially parallel to the electrode surfaces.

2. In an electrical precipitator through which flows a stream of gas carrying suspended particles to be removed, the combination of a discharge electrode; a substantially non-discharging collecting electrode; a foraminous substantially non-discharging grounded electrode intermediate the discharge and collecting electrodes; means for maintaining a high potential ionizing field between the discharge and intermediate electrodes; means for independently maintaining a non-discharging precipitating field between the intermediate and collecting electrodes with the collecting electrode of a polarity opposite to that of the discharge electrode; and means for directing the main stream of gas into, through, and out of the space between the discharge and intermediate electrodes in a direction substantially parallel to the electrode surfaces.

3. In an electrical precipitator through which flows a stream of gas carrying suspended particles to be removed, the combination of a discharge electrode; a substantially non-discharging collecting electrode; a foraminous substantially non-discharging electrode intermediate the discharge and collecting electrodes; means for independently maintaining a high potential ionizing field between the discharge and intermediate electrodes; means for maintaining a separate non-discharging precipitating field between the intermediate and collecting electrodes, said precipitating field being maintained in a direction to assist movement of charged particles toward the collecting electrode to collect thereon; and means for directing the main stream of gas into, through, and out of the space between the discharge and intermediate electrodes in a direction substantially parallel to the electrode surfaces.

4. In an electric precipitator through which flows a stream of gas carrying suspended particles to be removed, the combination of a discharge electrode; a collecting electrode system comprising a pair of substantially non-discharging electrodes of which one is a foraminous electrode positioned between the discharge electrode and the other non-discharging electrode; means

for independently maintaining a high potential ionizing field between the discharge electrode and the collecting electrode system; means for maintaining a separate non-discharging precipitating field between the pair of non-discharging electrodes; and means directing substantially all the gas flow, into, through, and out of the space between the discharge and foraminous electrodes in a direction substantially parallel to the electrode surfaces and maintaining a relatively quiescent zone between the electrodes of the collecting electrode system.

5. In an electric precipitator through which flows a stream of gas carrying suspended particles to be removed, the combination of a discharge electrode; a collecting electrode system comprising a pair of substantially non-discharging electrodes of which one is a foraminous grounded electrode positioned between the discharge electrode and the other non-discharging electrode; means for maintaining a high potential ionizing field between the discharge electrode and the collecting electrode system; means for maintaining a separate non-discharging precipitating field between the pair of non-discharging electrodes with the polarity of said other non-discharging electrode opposite to that of the discharge electrode; and means directing substantially all the gas flow into, through, and out of the space between the discharge and foraminous electrodes in a direction substantially parallel to the electrode surfaces, and maintaining a relatively quiescent zone between the electrodes of the collecting electrode system.

6. In an electric precipitator through which flows a stream of gas carrying suspended particles to be removed, the combination of a discharge electrode; a collecting electrode system comprising a pair of substantially non-discharging electrodes of which one is a foraminous grounded electrode positioned between the discharge electrode and the other non-discharging electrode; means for maintaining a high potential ionizing field between the discharge electrode and the collecting electrode system; means for maintaining a separate non-discharging precipitating field between the pair of non-discharging electrodes; and means directing substantially all the gas flow into, through, and out of the space between the discharge and foraminous electrodes in a direction substantially parallel to the electrode surfaces and maintaining a relatively quiescent zone between electrodes of the collecting electrode system.

7. In an electric precipitator through which flows a stream of gas carrying suspended particles to be removed, the combination of a discharge electrode; a collecting electrode system surrounding the discharge electrode and comprising a pair of substantially non-discharging cylindrical, co-axial electrodes of which one is an imperforate electrode, and the other is a foraminous grounded electrode between the discharge electrode and the imperforate electrode; means for maintaining a high potential ionizing field between the discharge electrode and the collecting electrode system; means for maintaining a separate non-discharging precipitating field between the foraminous and imperforate electrodes in a direction to assist movement of charged particles toward the imperforate electrode; and means directing substantially all the gas flow into, through, and out of the space between the discharge and foraminous electrodes in a direction substantially parallel to the electrode sur-

faces and maintaining a relatively quiescent zone between the electrodes of the collecting electrode system.

8. In an electric precipitator through which flows a stream of gas carrying suspended particles to be removed, the combination of a discharge electrode; a collecting electrode system comprising a pair of substantially non-discharging electrodes of which one is a foraminous electrode positioned between the discharge electrode and the second non-discharging electrode; means for maintaining a high potential ionizing field between the discharge electrode and the collecting electrode system; means for maintaining a separate non-discharging precipitating field between the pair of non-discharging electrodes; means directing substantially all the gas flow through the space between the discharge and foraminous electrodes and maintaining a relatively quiescent zone between the electrodes of the collecting electrode system; rapping mechanism for jarring deposited dust particles from said second non-discharging electrode; a hopper to catch dust jarred from said second non-discharging electrode; a second rapping mechanism for jarring deposited dust particles from the foraminous electrode; a second hopper to catch dust jarred from the foraminous electrode; and conveying means for removing dust from both hoppers.
9. In an electric precipitator through which flows a stream of gas carrying suspended particles to be removed, the combination of a discharge electrode; a collecting electrode system comprising a pair of substantially non-discharging cylindrical, co-axial electrodes of which one is an imperforate electrode, and the other is a foraminous grounded electrode positioned between the discharge electrode and the imperforate electrode; means for maintaining a high potential ionizing field between the discharge electrode and the collecting electrode system; means for maintaining a separate non-discharging precipitating field between the foraminous and imperforate electrodes in a direction to assist movement of charged particles toward the imperforate electrode; means directing substantially all the gas flow through the space between the discharge and foraminous electrodes and maintaining a relatively quiescent zone between the electrodes of the collecting electrode system; rapping mechanism for jarring deposited dust particles from the imperforate electrode; a hopper to catch dust jarred from the imperforate electrode; a second rapping mechanism for jarring deposited dust particles from the foraminous electrode; a second hopper to catch dust jarred from the foraminous electrode; and conveying means for removing dust from both hoppers.
10. In an electric precipitator through which flows a stream of gas carrying suspended particles to be removed, the combination of a discharge electrode; a collecting electrode system comprising a pair of substantially non-discharging electrodes of which one is an imperforate electrode, and the other is a foraminous electrode between the discharge electrode and the imperforate electrode; means for maintaining a high potential ionizing field between the discharge electrode and the collecting electrode system; means for maintaining a separate non-discharging precipitating field between the foraminous and imperforate electrodes; means directing substantially all the gas flow through the space between the discharge and foraminous electrodes and maintaining a relatively quiescent zone between the electrodes of the collecting electrode system; rapping mechanism for jarring deposited dust particles from the imperforate electrode; a hopper to catch dust jarred from the imperforate electrode; a second rapping mechanism for jarring deposited dust particles from the foraminous electrode; a second hopper to catch dust jarred from the foraminous electrode; and conveying means for removing dust from both hoppers.

zone between the electrodes of the collecting electrode system; rapping mechanism for jarring deposited dust particles from the imperforate electrode; an outer housing enclosing all said electrodes and having a hopper bottom adapted to catch dust jarred from the imperforate electrode; a second rapping mechanism for jarring deposited dust particles from the foraminous electrode; an inner housing forming a combined gas inlet header and hopper adapted to catch dust jarred from the foraminous electrode; and conveying means for removing dust from both hoppers.

11. In an electric precipitator through which flows a stream of gas carrying suspended particles to be removed, the combination of a discharge electrode; a collecting electrode system comprising a pair of substantially non-discharging electrodes of which one is a foraminous electrode positioned between the discharge electrode and the other non-discharging electrode; rapping mechanism for jarring deposited dust particles from the collecting electrode system; an outer housing enclosing all said electrodes and having a hopper bottom adapted to catch dust jarred from said other non-discharging electrode; an inner housing forming a combined gas inlet header and hopper adapted to catch dust jarred from the foraminous electrode; and conveying means for removing dust from both hoppers.

12. In an electric precipitator through which flows a stream of gas carrying suspended particles to be removed, the combination of a discharge electrode; a collecting electrode system comprising a pair of substantially non-discharging electrodes of which one is a foraminous electrode positioned between the discharge electrode and the other non-discharging electrode; rapping mechanism for jarring deposited dust particles from the collecting electrode system; an outer housing enclosing all said electrodes and having a hopper bottom adapted to catch dust jarred from said other non-discharging electrode; an inner housing forming a combined gas inlet header and hopper adapted to catch dust jarred from the foraminous electrode; and a continuous chain conveyor having an upper run moving dust from the inner hopper into the outer hopper, and a lower run removing dust from the outer hopper.

13. In an electrical precipitator through which flows a stream of gas carrying suspended particles to be removed, the combination of a grounded housing; a discharge electrode; a substantially non-discharging collecting electrode; a foraminous substantially non-discharging electrode intermediate the discharge and collecting electrodes; means for maintaining a high potential ionizing field between the discharge and intermediate electrodes; means for independently maintaining a separate non-discharging precipitating field between the intermediate and collecting electrodes; and gas impervious members connected to the housing and engaging the ends of the intermediate electrode where the gas enters and leaves the ionizing field to direct the main stream of gas into, through, and out of the space between the discharge and intermediate electrodes in a direction substantially parallel to the electrode surfaces.

14. In an electric precipitator through which flows a stream of gas carrying suspended particles to be removed, the combination of a discharge electrode; a collecting electrode system comprising a pair of vertically extending, cylin-

drical, substantially non-discharging electrodes, of which one is an imperforate electrode and the other is a foraminous electrode positioned between the discharge electrode and the imperforate electrode; an outer housing enclosing all said electrodes and having a hopper bottom adapted to catch dust falling from said imperforate electrode; an inner housing connected to the outer housing and forming a combined gas inlet header and hopper adapted to catch dust falling inside said foraminous electrode; and a nipple connected to the hopper and engaging the lower end of the foraminous electrode to direct the stream of gas upwardly into the space inside the foraminous electrode.

15. In an electric precipitator through which flows a stream of gas carrying suspended particles to be removed, the combination of a dis-

charge electrode; a collecting electrode system comprising a pair of substantially non-discharging electrodes of which one is a foraminous electrode positioned between the discharge electrode and the other non-discharging electrode; an outer housing enclosing all said electrodes and having a hopper bottom adapted to catch dust falling from said other non-discharging electrode; an inner housing connected to the outer housing and forming a combined gas inlet header and hopper adapted to catch dust falling inside said foraminous electrode; and a nipple connected to the hopper and engaging the lower end of the foraminous electrode to direct the stream of gas upwardly into the space inside the foraminous electrode. 5 10 15

HARRY J. WHITE.
